(57) **CLAIM**

The ornamental design for a sheet pile connector for connecting sheet piles, as shown and described.

DESCRIPTION

FIG. 1 is a perspective view of the sheet pile connector for connecting sheet piles according to my design; FIG. 2 is an end view of the sheet pile connector of FIG. 1, the opposite end view being a mirror image thereof; FIG. 3 is a front view of the sheet pile connector of FIG. 1; FIG. 4 is a rear view of the sheet pile connector of FIG. 1; FIG. 5 is a top view of the sheet pile connector of FIG. 1; and, FIG. 6 is a bottom view of the sheet pile connector of FIG. 1. The broken lines represent environment and form no part of the claimed design.
